US00D636988S

(12) United States Design Patent
Romero et al.

(10) Patent No.: US D636,988 S
(45) Date of Patent:  May 3, 2011

(54) HANDBAG WITH INTERCHANGEABLE
HANDBAG COVER

(75) Inventors: Michelle Romero, West Valley City, UT (US); Annette B. Cavaness, Provo, UT (US); Christian J. Seegmiller, Riverton, UT (US)

(73) Assignee: Miche Bag, LLC, South Jordan, UT (US)

() Term: 14 Years

(21) Appl. No.: 29/367,225

(22) Filed: Aug. 4, 2010

Related U.S. Application Data

(63) Continuation-in-part of application No. 11/945,174, filed on Nov. 26, 2007.

(51) LOC (9) CI. 03-01

(52) U.S. CI. D3/232

(57) CLAIM

The ornamental design for a handbag with interchangeable handbag cover, as shown and described.

DESCRIPTION

FIG. 1 is a top perspective view of the claimed base handbag with an exemplary interchangeable handbag cover shown in phantom in a closed, attached conformation about the base handbag;

FIG. 2 is a top perspective view thereof, with the exemplary interchangeable handbag cover shown in phantom in a partially opened, detached conformation about the base handbag;

FIG. 3 is an elevated front view of the base handbag shown in FIG. 1, with the opposing back view being a mirror image thereof;

FIG. 4 is a top, plan view thereof;

FIG. 5 is an elevated, left side view thereof, with the opposing right side being a mirror image thereof; and,

FIG. 6 is bottom view thereof.

The broken lines showing the interchangeable handbag cover is for illustrative purposes and forms no part of the claimed design.

The claimed design is shown broken away to indicate indeterminate length.

1 Claim, 3 Drawing Sheets
